ELEVATOR LOCK

Harold A. Flint, San Francisco, and Charles F. Lantz, Oakland, Calif.

Application October 4, 1947, Serial No. 777,978

7 Claims. (Cl. 187—31)

1

This invention relates to safety devices for elevators, and has for its principal object the provision of an elevator lock having the dual function of preventing operation of the elevator while the gate is in the open position, and preventing the opening of the gate while the elevator is at other than the floor level.

We accomplish the above by means of the mechanism described in the following specification and illustrated in the accompanying drawings forming a part hereof, and in which

Figure 1 is a front elevation of the locking mechanism with the housing cover removed.

Figure 2 is a side elevation, partly in section, as seen from line 2—2 of Figure 1.

Figure 3 is an elevation similar to Figure 2 as seen from line 3—3 of Figure 1.

Figure 4 is a fragmentary detail showing the device as applied to an elevator and shaft.

Referring to the drawing in detail, a rectangular housing 5 has a mounting plate 6, spaced apart from the back wall 7 thereof, for a portion of its length, to form a slot 8, therewith. Rectangular openings 9 and 10, in the wall 7 communicate with the slot 8.

Pivotedly mounted by shaft 11, in the upper end of the housing 5, is a latch 12 adapted to be operated by an arm 13 fixedly mounted on the exterior extending portion of the shaft 11. The arm 13 is provided with a roller 14 mounted at its swinging end. The latch 12 is adapted to swing from a gate engaging position as shown in solid lines on Figure 3, to the gate releasing position as shown in phantom.

Also pivotedly mounted within the housing 5, on a shaft 14, is a double latch 15 which has, secured to one side thereof, a mercury switch 16 wired to a terminal block 17 located on the back wall 7 near the lower end thereof. Upon installation of the safety device, wires are brought through an opening 18 in the bottom of the housing 5, and secured to the terminal block 17, putting the switch 16 in one side of the power circuit to the elevator motor.

The double latch 15 is adapted to swing from a switch closing position, as shown in solid lines on Figure 2, to a switch opening position as shown in phantom.

One of the safety devices is installed on the inner wall 19 of the elevator shaft, at each floor, as indicated on Figure 4. The elevator 20 is provided with a cam 21 adapted to engage the roller 14 and swing the arm 13 to open the latch 12 as shown in phantom on Figure 3.

The entrance to the elevator at each floor is

protected by a gate 22 fitted with a bar 23 adapted to enter the slot 8. These gates are always locked by the engagement of the bar 23 with the latch 12, as shown on Figure 3, and can only be released when the elevator is at the particular floor, by the action of the cam 21, as shown on Figure 4.

The upper edge of the mounting plate 6 is chamfered as at 24, and the top edge of the back wall 7 extends forwardly and upwardly to form a flange 25, both contributing to the easy entry of the bar 23 into the slot 8.

Referring to Figure 2, it will be seen that opening of the gate 22 will cause the bar 23 to engage the latch 15, at its upper hook 26, and swing it to the position shown in phantom, tripping the mercury switch 16 and breaking the power circuit to the elevator. With the switch 16 in this position, operation of the elevator is impossible. When the gate is closed, the bar 23 engages the latch 15 at its lower hook 27, and returns it to the switch closing position, allowing the elevator to be set in motion. An opening 28 in the mounting plate 6 provides clearance for the latches 12 and 15.

The housing 5 is normally closed by means of a sheet metal cover, which has been omitted on the drawings in the interest of clearer delineation of the interior mechanism.

While we have disclosed a preferred embodiment of our invention, it will be understood that modifications may be made within the spirit and scope of the appended claims.

We claim:

1. An elevator lock for use at a floor with an elevator and an elevator gate comprising: a first gate engaging latch adapted to be actuated by an elevator adjacent the floor, a second gate engaging latch adapted to be actuated by a gate, and an electric switch controlled by said second gate engaging latch for breaking and making the power circuit of an elevator, said second gate engaging latch being provided with a pair of spaced projections adapted to be successively engaged by opening and closing movements of the gate.

2. An elevator lock for use at a floor with an elevator and an elevator gate comprising: a first gate engaging latch adapted to be actuated by an elevator adjacent the floor, a second gate engaging latch adapted to be actuated by a gate, and an electric switch controlled by said second gate engaging latch for breaking and making the power circuit of an elevator, said second gate engaging latch being provided with a pair of spaced projections adapted to be successively

engaged by opening and closing movements of the gate, said first gate engaging latch being adapted to permit opening the gate only when so actuated by an elevator.

3. An elevator lock for use at a floor with an elevator and an elevator gate comprising: a first pivotally mounted gate engaging latch adapted to be actuated by an elevator for locking a gate in closed position except when so actuated, a second pivotally mounted gate engaging latch spaced from said first latch and adapted to open and close the power circuit of said elevator by the opening and closing movements of the gate.

4. An elevator lock for use at a floor with an elevator and an elevator gate comprising first and second gate engaging latches adapted to be successively and independently actuated by the elevator and gate respectively, said first latch being adapted to prevent opening of the gate except when so actuated, said second latch being adapted to open and close the power circuit of the elevator by the opening and closing movements of the gate.

5. An elevator lock for use at a floor with an elevator and an elevator gate comprising a housing having a slot extending longitudinally of the path of travel of such a gate, a first pivotally mounted gate engaging latch adapted to be actuated by an elevator for locking a gate in closed position except when so actuated, a second pivotally mounted gate engaging latch longitudinally spaced from said first latch and adapted to open and close the power circuit of said elevator by the opening and closing movements of the gate.

6. An elevator lock for use at a floor with an elevator and an elevator gate comprising a housing having a slot extending longitudinally of the path of travel of such a gate, a first pivotally mounted gate engaging latch adapted to be actu-

ated by an elevator for locking a gate in closed position except when so actuated, a second pivotally mounted gate engaging latch longitudinally spaced from said first latch and adapted to open and close the power circuit of said elevator by the opening and closing movements of the gate, a gate engaging tooth on said first latch for movement into and out of said slot depending upon the position of the elevator, a pair of longitudinally spaced projections on said second latch adapted to be successively engaged by the gate by opening and closing movements of the latter for swinging said latch out of and into circuit closing position.

15 7. An elevator lock for use at a floor with an elevator and an elevator gate comprising: a housing having a slot extending longitudinally of the path of travel of such a gate, a first gate engaging latch adapted to be actuated by an elevator for locking a gate in closed position except when so actuated, a second gate engaging latch swingably mounted on said housing and spaced longitudinally from said first latch, spaced projections on said second latch adapted to be 20 successively engaged by opening and closing movements of said gate, and a switch secured to said second latch actuated by swinging movements of the latter for opening and closing the power circuit to said elevator.
